UNITED STATES PATENT OFFICE

127,412

DESIGN FOR A HIGH WING MONOPLANE

Aristede A. Theodoropoulos, New Haven, Conn.

Application October 28, 1939, Serial No. 87,905

Term of patent 7 years

To all whom it may concern:

Be it known that I, Aristede A. Theodoropoulos, a citizen of the United States, residing in New Haven, in the county of New Haven and State of Connecticut, have invented a new, original, and ornamental Design for a High Wing Mono-plane, of which the following is a specification, reference being had to the accompanying drawings, forming part thereof, in which

Fig. 1 is a top plan view of a high wing mono-plane showing my new design;

Fig. 2 is a front elevational view of the said monoplane design;

Fig. 3 is a side elevational view of said mono-plane design.

Fig. 4 is a bottom plan view of the monoplane; and

Fig. 5 is a fragmentary sectional view on line 5—5 of Fig. 1.

I claim:

The ornamental design for a high wing mono-plane, substantially as shown.

ARISTEDE A. THEODOROPULOS.
